UNITED STATES PATENT OFFICE

LEWIS T. WILCOX, OF PEEKSKILL, NEW YORK

OIL BURNER

Application filed January 13, 1928. Serial No. 246,406.

My invention relates to oil burners such as is disclosed in the Homan patent reissued Nov. 22, 1927 No. 16,794 and in a copending application filed in the name of W. C. Homan Serial No. 223,299, filed October 1, 1927, and used in household or other stoves and heaters. As shown in the above patent and application my invention pertains to burners which comprise generally a double walled tubular burner shell housing a wick holder slideable longitudinally and vertically in the shell. The shell and wick are usually supplied with oil from an external tank through suitable piping.

It is the purpose of this invention to provide a wick holder readily adjustable in the burner shell, to provide a suitable limiting stop for the wick capable of being locked in position and to provide a reversible wick holder which may be inserted in any position without disturbing the operation of the raising medium. An additional feature is the particular manner of securing the burner to the burner base, constituting a resilient hook.

I accomplish the above objects by forming vertical ribs upon one of the walls of the burner which serve as guides for the wick holder and by cutting longitudinal diametrically opposite slots in the wick holder and forming racks on the four edges thereof which cooperate with a toothed member extending across the holder to raise or lower the holder. The toothed rod is set off from the center of the holder a distance substantially equal to the depth of the rack tooth to cause it to engage the teeth on one side of the slots only.

A tubular wick stop is provided which slides within the inner wall of the burner shell and is guided upon ribs formed upon the inner wall of the shell, the stop member having projecting portions extending into the path of travel of the wick. An operating rod is secured to the stop member and projects through the burner by means of which the stop member may be raised or lowered and locked in either position. A generally U-shaped clamping hook each arm of which is bent into a reverse curve to give it greater elasticity is pivotally secured to the burner

and extends therebelow to engage and hook over the fuel pipe.

A detailed description will be given in connection with the drawings in which:

Fig. 1 is a longitudinal section through a burner shell and a portion of the base structure;

Fig. 2 is a similar section taken on a plane perpendicular to that of Fig. 1;

Fig. 3 is a section on line 3—3 of Fig. 1; 60

Fig. 4 is a transverse section below the upper surface of the wick stop of a slightly modified form illustrating a different wick adjustment;

Fig. 5 is a plan of a burner shell, wick, 65 wick holder and wick stop, constructed in accordance with this invention;

Fig. 6 is a longitudinal section through a modified form of burner shell;

Fig. 7 is a side elevation of a wick holder 70 and adjusting rod, and

Fig. 8 is a section on line 8—8 of Fig. 6.

In the embodiment of my invention illustrated particularly in Figs. 1, 2, 3 and 5 there is shown a burner shell comprising an outer tubular wall 1, the upper end of which is flanged outwardly to form a seating ledge 2 for a drum (not shown) and a concentric tubular inner wall 3 also having a flanged upper end providing a seating ledge 3a for means later described. The two walls are spaced apart sufficiently to permit a wick 4 attached to wick holder 5' to slide longitudinally therebetween. At the bottom end the two walls are crimped together thus forming 80 a fuel well for the wick which well is fed from the usual external tank (not shown) through the usual elbow 5, pipe connection 6 leading to fuel pipe 7 and connected thereto by a packing nut 7a. The lower end of the burner shell rests upon the upper end of a sub-shell or base 8 seating upon an inturned flange 9 formed in the upper end of sub-base 8 just below the upper edge thereof. The burner shell and sub-base may be riveted, welded or otherwise permanently secured together if so desired. The lower end of the sub-base seats upon a raised annular seating flange 10 struck up from the burner base 10a in a manner similar to that disclosed in my applica- 100

tion Serial No. 223,299. The entire assembly is secured to the base 10 by means of a generally V-shaped bale or hook wire 11 the arms 12 of which are secured to a cross bar 13 attached to the inner wall 2 at diametrically opposite points, the arms being bent into a double or reverse curve joined at the lower ends by a hook portion 14 adapted to extend through an opening in the burner base and be sprung over the supply pipe 7 lying below the burner base.

To insure easy sliding movement of the wick holder the outer wall 1 is formed with spaced vertical inwardly depressed ribs 18 which serve as spacing and guiding means for the wick holder in its longitudinal movements. The lower portion of the wick holder is provided with two diametrically opposite longitudinal slots, all four edges of which have plates 19 secured thereto having rack teeth 20 formed upon the opposing edges thereof, shown more particularly in Figs. 7 and 8. A toothed or splined rod 21 extends across the burner shell within a sheath 21a and is supported in suitable bearings 22 and 23 in the shell substantially as disclosed in the reissued Patent No. 16,794. The rod does not extend diametrically across the center of the burner shell but is offset from the center a distance substantially equal to the depth of the teeth of the racks. The rod is of such diameter that it will engage only the teeth on one side of the slots and clear the teeth on the other side. Thus regardless of which of the two possible ways the holder is inserted in the shell and placed over the rod with the teeth of the rod engaging the teeth of the racks, rotation of the rod 21 in a given direction will always raise the holder, and rotation in the reverse direction will always lower the holder. Any suitable knurled handle 24 may be secured to the rod for turning the same.

The inner wall 2 has longitudinally vertical guiding ribs 25 projecting inwardly therefrom formed by striking vertical depressions in the wall at spaced intervals. These depressions form guides for an inverted cup shaped skirt portion 26 of a dish shaped longitudinal movable wick stop member 27 which latter element is riveted to the center portion of the skirt which has the center thereof raised to space the stop member from the remainder of the top of the skirt portion. The side walls of the cup are perforated as at 28 to provide communication with the space 29 between the skirt and inner wall. The stop member 27 has tongues 30 struck downwardly therefrom to provide additional support for the stop member 27 and to provide apertures 31 therein to permit air to pass therethrough. Additional openings 32 are formed in the stop member for the same purpose. The dish shaped stop member is formed with upwardly extending

lugs 33 which are bent outwardly at their extremities to provide horizontal fingers 34 lying in the path of movement of the wick to constitute a limiting stop for the wick. In its lowermost position the stop member 70 seats on ledge 3a formed in the upper end of the inner wall of the burner shell. The stop member may be raised or lowered by means of a rod 35 secured at its upper end to the under side of the top of the skirt 26 and extending downwardly through the burner. The lower end is bent outwardly as at 36 and projects exteriorly of the shell through a U-shaped slot 37 cut in the sub-base and by means of which the stop member may be 80 locked in raised or lowered position. A suitable handle 38 is fastened to the outer end of the rod.

Combustion takes place between two concentric perforated tubes (indicated in Fig. 2). 85 The lower end of the outer tube rests upon seat 2 and the inner tube rests upon a ledge 39 formed in the stop member 27.

In Fig. 4 there is illustrated a slightly modified form in which the wick holder is 90 raised or lowered by means of an inclined rod 21' having a gear 40 upon its lower end adapted to engage perforations 41 in the wick holder, the gear and lower end of the rod 21' being enclosed in a cap 42. By this 95 arrangement the slot 37 may be cut in the front of the sub-base and the rod 35 may be brought out at the front of the burner. In all other respects this modification is similar 100 to that shown in Figs. 1, 2, 3 and 5.

In the modification shown in Figs. 6, 7 and 8 I have illustrated my off center wick drive applied to a simpler form of burner. In this embodiment the wick stop is omitted as is the sub-shell or base and the walls of the burner shell converge slightly at their upper ends. 105 In other respects the burner is substantially the same as illustrated in the other figures.

It will be noted that in this construction the ribs 18 are of the depth of the flare of the outer wall 1 and consequently form guide rails in line with the top edge of the wall. The combined thickness of the wick and wick holder is equal to the space between the walls at their upper edge, and consequently the wick is spaced from the inner wall a distance equal to the outward flare of that wall. This clearance of the wick and holder from both walls which is maintained by the ribs enables 115 the wick to move easily. The metallic wick holder slides upon these rails with negligible friction, and furthermore the trouble arising from the tendency of rust to accumulate on the relatively movable metallic surfaces and 120 impair the facility of movement of the wick holder is eliminated.

It follows from the foregoing that I have provided a simply constructed burner which is practically foolproof, one that may be 125 readily cleaned, one in which the wick will 130

always be freely movable and one which may be readily disassembled for cleaning and renewal purposes. The particular wick raising structure makes it impossible to replace a wick holder in a wrong position since either way is a correct one. The vertical guiding ribs provide channelways therebetween which will allow any particles of carbon or other foreign substances to fall down without binding the wick. My particular wick stop member is also free in its operation and may be easily raised or lowered without dismantling the burner whenever it is desired to raise the wick above a normal burning height for trimming or cleaning purposes, and the entire burner may be quickly and readily removed if so desired by unhooking the hook 14 and loosening the packing nut 7a.

It is obvious that minor changes may be made in the design and details of structure without departing from the spirit and scope of the invention as defined in the appended claims.

I claim:

1. In a liquid fuel burner, a longitudinally movable wick holder provided with diametrically opposite longitudinal slots having racks on both edges thereof and a single toothed rod extending across said wick holder and positioned off center substantially the depth of the teeth of said racks, said slots being of a width greater than the diameter of said rod by at least the depth of said teeth.

2. In a stove, a burner base, an open burner seat in said base, a fuel supply pipe extending across said burner seat, a burner on said seat and a substantially V-shaped wire hook member depending from said burner through the open burner seat, the arms of said member being reversibly curved and joined at their ends by a hook portion adapted to be releasably hooked under the supply pipe to secure the burner thereto.

3. In a liquid fuel burner, a double walled tubular burner shell, a longitudinally movable wick and wick holder slidably mounted between said walls and a longitudinally movable tubular wick stop member slidably supported within said shell and having portions thereof extending into the path of movement of said wick, the inner wall of said shell having ribs thereon for guiding said stop member.

4. In a liquid fuel burner, a double wall tubular burner shell, a longitudinally movable wick and wick holder slidably mounted between said walls, a longitudinally movable tubular wick stop member slidably supported within said shell and having portions thereof extending into the path of movement of said wick, the inner wall of said shell having guides thereon for guiding said stop member, and means for raising or lowering said stop member.

5. In a liquid fuel burner, a double walled tubular burner shell, a longitudinally movable wick and wick holder slidably mounted between said walls, a longitudinally movable tubular wick stop member slidably supported within said shell and having portions thereof extending into the path of movement of said wick, the inner wall of said shell having guides thereon for guiding said stop member, means for raising or lowering said stop member and means for locking said stop member in a raised or lowered position.

6. In a liquid fuel burner, a double walled tubular burner shell, a longitudinally movable wick and wick holder slidably mounted between said walls, a longitudinally movable tubular wick stop member slidably supported within said shell and having portions thereof extending into the path of movement of said wick, the inner wall of said shell having guides thereon for guiding said stop member, means for raising or lowering said stop member comprising a rod depending from said stop member and extending exteriorly of said shell.

7. In a liquid fuel burner, a double walled tubular burner shell, a longitudinally movable wick and wick holder slidably mounted between said walls, a longitudinally movable tubular wick stop member slidably supported within said shell and having portions thereof extending in the path of movement of said wick, the inner wall of said shell having guides thereon for guiding said stop member, means for raising or lowering said stop member, comprising a rod depending from said stop member and extending exteriorly of said shell, said shell having a U-shaped slot therein through which said rod projects whereby said stop member may be locked in its raised or lowered position.

8. A liquid fuel burner comprising a tubular burner shell, a tubular wick holder fitting and slideable within said shell and having two longitudinal diametrically opposed slots of the same width extending from the bottom edge of the holder, both side edges of each slot being toothed to constitute a rack, and an actuating rod for the wick holder extending across and bearing in the shell in the range of the said slots when the wick holder is in the shell and having pinion teeth on its two portions received within the slots, said rod being disposed with its axis parallel to the diametrical line intersecting the center lines of the slots and offset therefrom so that its pinion teeth engage the rack teeth of both slots on one side and are clear of the rack teeth on the other side of the said diametral line.

9. In a stove, a fuel supply pipe, a tubular burner seated upon the pipe, and means for resiliently hooking the burner to the pipe comprising a hook depending directly underneath the burner and attached to the in-

terior of the burner substantially above its bottom edge, the attaching arm being of resilient wire having in its length a reverse curve to permit the length of the hook from 5 its point of attachment to be resiliently expanded and the proportions of the parts being such that the hook springs underneath the pipe and holds the burner on the pipe under spring tension.

10. In a stove, a fuel supply pipe, a tubular burner seated upon the pipe, and means for resiliently hooking the burner to the pipe comprising a substantially V-shaped wire hook member depending from the burner in 15 substantially the axis thereof, the arms of the hook member being reversely curved and joined at their ends by a hook portion adapted to be releasably hooked under the supply pipe to secure the burner thereto.

20. In witness whereof, I hereunto subscribe my signature.

LEWIS T. WILCOX.
